Primary Examiner—T. Chase Nelson*Assistant Examiner*—Kathleen M Sims*(74) Attorney, Agent, or Firm*—Crossley Patent Law; Mark A. Crossley(57) **CLAIM**

The ornamental design for a portable toilet, as shown and described.

DESCRIPTION

FIG. 1 is a front elevation view of a portable toilet showing my new design;

FIG. 2 is a rear elevation view thereof;

FIG. 3 is a side elevation view thereof;

FIG. 4 is a top plan view thereof;

FIG. 5 is a bottom plan view thereof;

FIG. 6 is an isometric view thereof; and,

FIG. 7 is an opposite side elevation view thereof.

The broken lines in the drawings depict environmental subject matter only and form no part of the claimed design.
